CLAIM

The ornamental design for exerciser, as shown and described.

DESCRIPTION

FIG. 1 is a perspective view of an exerciser showing our new design;

FIG. 2 is a side elevational view thereof;

FIG. 3 is a front elevational view thereof;

FIG. 4 is a top plan view thereof;

FIG. 5 is a side elevational view of the side opposite that shown in FIG. 2;

FIG. 6 is a rear elevational view thereof; and,

FIG. 7 is a bottom plan view thereof.
